CLAIM

We claim the ornamental design for a display screen or portion thereof with a graphical user interface, as shown and described.

DESCRIPTION

The FIGURE is a front view of a display screen or portion thereof with graphical user interface.

The outer broken-line rectangle shows the perimeter of a portion of a display screen and forms no part of the claimed design. The remaining broken lines show features of the graphical user interface and form no part of the claimed design.

1 Claim, 1 Drawing Sheet
